(57) **CLAIM**

The ornamental design for a support for projector, as shown and described.

DESCRIPTION

FIG. 1 is a front, right side, top perspective view of a support for projector showing our new design;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof;

FIG. 7 is a bottom plan view thereof;

FIG. 8 is a front, left side, bottom perspective view thereof;

FIG. 9 is a front, right side, top perspective view thereof, showing a state in which an arm part is extended;

FIG. 10 is a front, right side, top perspective view thereof, showing a state in which an arm part is shortened; and,

FIG. 11 is a reduced scale reference view thereof, showing a state in which a projector is attached to this article.

The portions of the article shown in broken lines in the figures are for illustrative purposes only and form no part of the claimed design.
